UNITED STATES PATENT OFFICE

WILBERT S. MAHR, OF LYNN, MASSACHUSETTS

PALLET HOLDER

Application filed April 15, 1931. Serial No. 530,411.

This invention relates to pallet holders for the use of jewellers when securing stones to the pallets and has for its object the production of a simple and inexpensive tool of this character which will be very effective when in use.

This object is attained by the device illustrated in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings

Figure 1 represents a plan of pallet holder embodying the principles of the present invention.

Figure 2 represents a side elevation of the same, a portion thereof being shown in section.

Figure 3 represents a partial plan of the same with clamp lever removed.

Figure 4 represents an end elevation of the holder.

Figure 5 represents an end elevation of the outer end of the clamp lever, and

Figures 6, 7 and 8 represent plans of various forms of pallets adapted to be held in said holder.

Similar characters indicate like parts throughout the several figures of the drawings.

In the drawings, 10 is a cylindrical metal handle forked at one end, as indicated at 11 and having an extension 12.

Supported by and secured to this extension 12 with one end thereof extending into the forked end 11 of the handle 10 is a support 13 from the forward end of which extends downwardly a pair of pins 14.

The support 13 is composed of an imperforate plate 15 and a superimposed perforated plate 16.

These two plates 15 and 16 are riveted together by rivets 17 and the upper ends 18 of the depending pins 14.

The whole support is also secured by the rivet 19 to the handle 10.

One of the perforations 20 in the upper plate 16 is substantially rectangular, as indicated in Fig. 3 of the drawings, while adjacent thereto is a substantially elliptical opening 21 in the plate 16, as shown in said Fig. 3.

The under plate 15 has a groove 22 cut into the upper face thereof aligned with a slot 22a in the upper plate 16 (see Fig. 3).

Located within the opening 20 are two cylindrical depressions 23 and 24 formed in the under plate 15 and adapted to receive the pivot pins of pallets.

These depressions 23 and 24 are of different sizes to accommodate them for the pivot pins of different sizes of pallets.

Within the opening 20 and formed in the upper face of the lower plate 15 is another cylindrical depression 25 which is used to position on the support 13, the form of pallet shown in Fig. 7.

Extending upwardly from the handle 10 and riveted thereto is a supporting member 26 having pivoted thereto at 27, a clamp lever 28, the forward end 29a of which is adapted to be held normally in contact with the upper plate 16 by means of a spring 27a.

This spring 27a is secured at 28a to the handle 10 and its free end extends into a slot 29 on the under side of the clamp lever 28.

The forward end 29a of the clamp lever 28 is provided with a slot 30 parallel with the groove 22 in the upper face of the under plate 15 and also with the slot 22a in the upper plate 16.

One wall of the opening 20 has curvatures 31 therein upon either side of the groove 22, these curvatures 31 in the wall of the opening 20 assisting in properly positioning the pallet on the support 13 when its pivot is in one of the depressions 23 and 24.

In Fig. 6 of the drawings is shown a pallet 32 having a pivot pin 33 adapted to be inserted into the hole 24 and provided with an arm 34 adapted to be positioned in the slot 22a.

The forked end 35 of the arm 34 rests on the upper face of the under plate 15 within the perforation 21 with the pin 36 therein extending into the groove 22.

6. The curved ends 37 rest against a wall of the perforation 20.

When the lever 28 is lowered so that its forward end 29 is rests on the pallet 32 the upper end of the pivot pin will be positioned 10 in the slot 30 thereof.

By these means the pallet 32 will be firmly held so that the workman may insert the pallet stones 38 into the slots 39.

15 Before these pallet stones 38 are inserted into the slots 39 the inner ends thereof are covered with shellac or some similar material and then the support 13 is placed over a flame to heat the shellac sufficiently to soften it and permit the stone 38 to be accurately adjusted.

20 When the shellac hardens the stone will be retained permanently in adjusted position.

As the lower plate 15 is imperforate the flame cannot contact with any part of the pallet 32 and injure or discolor the same.

25 A smaller pallet 40 is shown in Fig. 8 which is retained in position in the same manner, the pivot pin 41 in this case being inserted into the depression 23.

30 In Fig. 8 the pallet 40 is shown without the pallet stones 38 positioned in the slots 39.

Another form of pallet is shown in Fig. 7, this pallet 42 having a pivot pin 43 adapted to be inserted into the depression 24 and another pin 44 adapted to be inserted into 35 the depression 25.

40 When the pallets are clamped in position on the support 13 the insertion of the pallet stones 38 into the slots 39 is greatly facilitated and should a stone be dropped by the workman during the operation, it will fall onto the lower plate 15 within the perforation 20 where it may be picked up readily.

When the tool is not in use it is supported 45 on a table or bench by the pins 14.

Having thus described my invention, I claim:

1. In a pallet holder, a handle; an imperforate plate secured to one end thereof and provided in the upper face thereof with depressions to receive the pivot pins of pallets; an immovable plate superimposed thereon 50 and provided with two perforations to receive the body portions of said pallets; a perpendicular support on said handle; and a spring-pressed clamp lever pivoted thereto and having a forked end normally contacting with said perforated plate at a point between said perforations.

60 2. In a pallet holder, a handle; an imperforate plate secured to one end thereof and provided with means for positioning the pivot pins of pallets; an immovable plate superimposed thereon and provided with two perforations to receive the body portions of said pallets; widely separated supporting pins

extending downwardly from said imperforate plate; a perpendicular support on said handle; and a spring-pressed clamp lever pivoted thereto and having a forked end normally contacting with said perforated plate 70 at a point between said perforations.

3. In a pallet holder, a handle; an imperforate plate secured to one end thereof; an immovable plate superimposed thereon having alined perforations to receive the body 75 portions of pallets; depressions in the upper face of the under plate to receive the pivot pins of said pallets; a perpendicular support on said handle; and a spring-pressed clamp lever pivoted thereto and having a forked end normally contacting with said perforated plate 80 at a point between said perforations.

4. In a pallet holder, a handle; an imperforate plate secured to one end thereof; an immovable plate superimposed thereon and secured thereto, the perforations in which are of considerable size and connected by a narrow slot; a perpendicular support on said handle; and a spring-pressed clamp lever pivoted thereto and having a forked end normally contacting with said perforated plate 85 at a point above said slot.

5. In a pallet holder, a handle; an imperforate plate secured to one end thereof and having in its upper face an elongated depression and cylindrical depressions adapted to receive the pivot pins of pallets; an immovable plate superimposed thereon and provided with perforations to receive the body portions of said pallets; a perpendicular support on said handle; and a spring-pressed clamp lever pivoted thereto and having a forked end normally contacting with said perforated plate 95 at a point between said perforations.

6. In a pallet holder, a handle; an imperforate plate secured to one end thereof and having in its upper face an elongated depression and cylindrical depressions adapted to receive the pivot pins of pallets; an immovable plate superimposed thereon having alined perforations to receive the body portions of pallets, one of said perforations being above 100 said elongated depression; and clamping means for said pallets at a point between 115 said perforations.

7. In a pallet holder, a handle; an imperforate plate secured to one end thereof and provided with pin receiving depressions; an immovable plate superimposed thereon having large perforations in alinement and connected by a narrow slot, said slot and perforations being adapted to receive the body portions of pallets; a perpendicular support on said handle; and means for clamping the 120 pallets positioned in said perforations.

8. In a pallet holder, a handle; an imperforate plate secured to one end thereof and provided with pin receiving depressions; a 125 perforated plate superimposed thereon hav-

ing connected perforations therein adapted to receive the body portions of pallets; supporting pins extending downwardly from said imperforate plate; and means for clamping a pallet to said perforated plate.

5 9. In a pallet holder, a handle; an imperforate plate secured to one end thereof; an immovable plate superimposed thereon having connected perforations therein adapted to receive the body portions of pallets; depressions in the upper face of the under plate to receive the pivot pins of said pallets; and means for clamping a pallet to said perforated plate at a point between said perforations.

10 10. In a pallet holder, a handle; an imperforate pallet supporting plate secured to one end thereof provided in its upper face with a plurality of depressions for positioning said pallet; an immovable plate secured to the upper face of said imperforate plate provided with a plurality of perforations to receive the body portion of a pallet; and means for clamping the pallet to said supporting plate.

15 11. In a pallet holder, a handle; a support at one end thereof having two walled pallet-receiving recesses in the upper face thereof connected by a narrow slot and provided with depressions extending downwardly from these recesses adapted to receive the pins of said pallets; and means for clamping said pallets at a point above said connecting slot.

20 12. In a pallet holder, a handle; a support at one end thereof having two walled pallet-receiving recesses in the upper face thereof connected by a narrow slot and provided with cylindrical depressions extending downwardly from one of these recesses and an elongated depression extending downwardly from the other recess, said depressions being adapted to receive the pins of said pallets; and means for clamping said pallets at a point above said connecting slot.

25 Signed by me at 294 Washington St., Boston, Mass., this 4th day of April, 1931.

WILBERT S. MAHR.
